SWIMMING CAP

Philip Allen Wilson Haffenden, Deal, Kent, England, assignor to W. W. Haffenden Limited, Sandwich, Kent, England, a company of Great Britain

Filed July 14, 1967, Ser. No. 7,797

Claims priority, application Great Britain May 19, 1967

Term of patent 3½ years

(Cl. D2—238)

FIG. 2.

FIG. 1 is a side elevational view of a swimming cap showing my new design, the side opposite being a mirror image thereof; and

FIG. 2 is a top plan view thereof.

I claim:

The ornamental design for a swimming cap, as shown and described.
